N° 1,629.

TYRIAN
Shoe.

Patented Aug. 12, 1863.

Dec 16 29

Henry G. Tyer, of Andover, Mass.,
Letters Patent No. 1629, dated Aug. 12, 1862,

The schedule referred to in these Letters Patent and making part of the same

Be it known that I, Henry G. Tyer, of Andover in the County of Essex and State of Massachusetts, have invented a new and improved Design for a Trade Mark for shoes; and I do hereby declare that the following is a full, clear and exact description of the same, reference being had to the accompanying drawing forming part of this specification, which drawing shows my improved design for a trade mark stamped within a shoe.

To enable others skilled in the art to fully understand my invention I will describe it.

My improved design for a trade mark is composed of the letters "TYRIAN SHOE," and is intended to be stamped or printed or otherwise applied to some part of a shoe, substantially as shown in the drawing. The said letters are surrounded by a border representing the form of a shield, accompanied by a number, as, for example, "2," to signify the size of the shoe.

What I claim as new and desire to secure by Letters Patent, is

The design for a trade mark for shoes, herein shown and described.

Witnesses,

David Gray, }
John A. Henry, }

Henry G. Tyer.
